[57] CLAIM

The ornamental design for a wall mountable support bracket, as shown and described.

DESCRIPTION

FIG. 1 is a perspective view from the front, left side and above, of a wall mountable support bracket showing my new design;

FIG. 2 is a left side elevational view thereof, the right side being a mirror image thereof;

FIG. 3 is a top plan view thereof on a smaller scale;

FIG. 4 is a front elevational view thereof;

FIG. 5 is a rear elevational view thereof;

FIG. 6 is a bottom plan view thereof;

FIG. 7 is a left side elevational view thereof, with the support plate in a forwardly tilted position;

FIG. 8 is a top plan view thereof, shown at a reduced scale with the support plate turned at an angle; and,

FIG. 9 is a top plan view thereof, with the support plate turned at an angle in the opposite direction.

FIG. 1

FIG. 2

FIG. 3FIG. 4FIG. 5FIG. 6FIG. 8

FIG. 9
